UNITED STATES PATENT OFFICE.

GEORGE LANE, OF NEW YORK, N. Y., ASSIGNOR TO ORRIN BENEDICT & CO.,
OF BETHEL, CONNECTICUT.

IMPROVEMENT IN SWEAT-BANDS FOR HATS AND CAPS.

Specification forming part of Letters Patent No. **146,692**, dated January 20, 1874; application filed December 12, 1873.

To all whom it may concern:

Be it known that I, GEORGE LANE, of the city, county, and State of New York, have invented an Improved Sweat-Band for Hats and Caps, of which the following is a specification:

The invention consists in a hat or cap sweat-band, having its fore part, that fits the forehead of the wearer, made of leather, and leaving its main portion, that is in contact with the hair, made of silk. This enhances the durability of the sweat-band very materially, because it presents a material to the greasy hair that will not be injuriously affected by it; and which, moreover, does not make such an ill-ventilated hat as a continuous leather band would, and therefore conduces to a more healthful condition of the hair, and tends to reduce the liability to baldness which is so often caused by approximately air-tight coverings for the head, confining within them vapid and noxious air and exhalations.

The accompanying drawing represents a perspective view of the hat, looking in at the sweat-band.

The hat represented is nowise different from those now in common use, except in regard to its sweat-band, which, as before mentioned, is made partly of leather and partly of silk, or other woven fabric. Its fore part A, which comes in contact with the forehead, is made of the smooth leather of which sweat-bands are ordinarily made; but its main portion, which is in contact with the hair and does not need to be so smooth, for comfort's sake, is made of silk, and affords to the hat greater facility for ventilation, as it does not form such an air-tight fit around the head. Moreover, the durability of the sweat-band is increased, inasmuch as a material to which the grease of the hair is only slightly injurious is substituted for one that is very materially affected by it, especially

when enameled. This may seem an unimportant point, but, if so, a great mistake is made, for the hair is always greasy, whether artificial grease is applied to it or not, and, in time, leather becomes rotten, when subjected perpetually to the action of the grease, and although it may not be destroyed, yet it assumes a filthy loathsome appearance, and oftentimes causes the hat to be thrown aside as worn out long before it ought to be consigned to such a fate. Besides this, leather forms such an air-tight fit around the head that it confines within the hat air rendered vapid and unwholesome by the exhalations from the head, and engenders baldness and other diseases of the scalp. The openings among the meshes of the silken fabric, together with the interstices among the hairs of the head, afford a greater facility for a proper ventilation, which so much conduces to a healthy condition of the scalp, and obviates, in a great measure, premature baldness—that great scourge of modern times.

A hat furnished with such a sweat-band is incomparably cooler for summer use than one made of leather, and yet is abundantly warm for winter wear.

The silk and leather are united by pasting or sewing, and the sweat-band so formed is secured within the hat in the usual way.

What I claim as my invention is—

The hat or cap sweat-band having its fore part, that fits the forehead, made of leather, and its main portion, which is in contact with the hair, made of silk or other woven fabric, substantially as and for the purpose herein set forth.

GEO. LANE.
